UNITED STATES PATENT OFFICE.

LOUIS HUNYADI, OF CLEVELAND, OHIO.

RAIL JOINT AND CHAIR.

1,104,193.

Specification of Letters Patent. Patented July 21, 1914.

Application filed April 24, 1914. Serial No. 834,117.

To all whom it may concern:

Be it known that I, LOUIS HUNYADI, a subject of the King of Hungary, residing at Cleveland, in the county of Cuyahoga and State of Ohio, have invented certain new and useful Improvements in Rail Joints and Chairs, of which the following is a specification.

This invention relates to new and useful 10 improvements in rail joint and chair.

The primary object of this invention is to provide a joining means for the adjacent ends of railway rails obviating the use of the ordinary fish plates and requiring no 15 bolts or removable locking means.

A further object is to provide a connecting block for railway rails and adapted for hook engagement with the ends of adjacent rails whereby the rails are securely connected together in accurate alignment without the employment of any other means while the connecting block provides an intermediate short section of rail tread.

A still further object is to provide a connecting block slidably engaging a rail chair and having a short track section adapted for connecting together the adjacent ends of track rails.

With these general objects in view and others that will appear as the nature of the invention is better understood, the same consists in the novel combination and arrangement of parts hereinafter fully described, illustrated in the accompanying drawings and pointed out in the appended claim.

In the drawings forming a part of this application and in which like designating characters refer to corresponding parts throughout the several views:—Figure 1 is 40 a side elevation of two rails provided with the present joining block mounted upon a rail chair, portions being broken away. Fig. 2 is a top plan view thereof. Fig. 3 is a vertical transverse sectional view taken 45 upon line III—III of Fig. 1. Fig. 4 is an enlarged side elevation of the connecting block positioned between the end portions of two rails illustrating one of said rail portions in the assembling operation, the same being illustrated in dotted lines in its completely connected position. Fig. 5 is a perspective view of the connecting block detached. Fig. 6 is a perspective view of the end portion of a rail, and Fig. 7 is a perspective view of the mounting portion of a

chair or end portion of a tie adapted for supporting the connecting block.

Referring more in detail to the drawings, two rails 10 and 11 are illustrated of identical form and designed when taken with the connecting blocks shown in Fig. 5 for forming the continuous rails of the railroad track. A rail chair or metallic tie adapted for seating a rail upon each opposite end thereof is provided of the form illustrated in Fig. 7 and being formed of a channel bar 12 having opposite cut away notches 13 in each opposite side 14 thereof and adapted to communicate with the top slot 15 of the channel bar.

A connecting block as illustrated in Fig. 5 is supplied with a central rail portion 16 having a supporting web 17 with longitudinal base flanges 18, which flanges are adapted for sliding reception within the notches 13 of the channel rail 12 with the web 17 of the block positioned in the slot 15 of said channel rail. The connecting block is provided with sockets 19 at its opposite ends and communicating with the vertical slots 20 of the web 17 and which slots 20 are open at their tops and ends, the sockets 19 having one inclined inner face 21 and the upper edges of the web 17 on each side of the slots 20 having inclined faces 22 adjacent the tread portion 16 of the block. The opposite ends of the rails 10 and 11 are formed identically with hooks 23 outwardly projecting from the rail web 24 while the rail web is cut away beneath the hook 23 forming an inclined lower surface 25 merging with the outwardly slanting end 26 of the base flange 27 of the rail.

With the provision of the rail chair shown in Fig. 7, the block 17 is readily positioned thereon by sliding the block into the top opening of the chair and with the block tread 16 positioned transversely of the chair and above the opening therein as best illustrated in Fig. 2. The two rails 10 and 11 are then readily attached to the block by tilting the rails sufficiently to allow an insertion of the end hook 23 into the block socket 19 as illustrated in Fig. 4 which forms upon completion a solid locking engagement between the rail end and the block and with the slanting face 21 of the socket 19 engaging the inner inclined face 28 of the hook 23. The inclined faces 22 of the slotted web portions accommodate the end of the rail 110

tread when the rail end is being hooked to the connecting block. It will be seen that with the block securely positioned upon the chair or the tie the two rails may be thus 5 readily engaged with the opposite ends of the block and with the tread portion 16 of the block in alinement with the tread portions of the two connected rails and thus forming a continuous track rail. It should 10 be noted that upon a completion of the formation of the rail as illustrated in Fig. 4 with the rail 11 engaging the block, that the track is then continued by engaging the rail 10 with the opposite side of the block 15 while a further block is then connected in a similar manner to the free end of the rail 10 and another rail connected to said rail 10 by a similar engagement with the newly 20 added block and in which manner the continuous track rail may be speedily built up without the employment of fish plates or bolts of any form.

While the forms of the invention herein shown and described are what are believed 25 to be preferable embodiments thereof, it is nevertheless to be understood that minor changes may be made in the form, proportion and details of construction without departing from the spirit and scope of the in- 30 vention as set forth in the appended claim.

What I claim as new is:—

A device of the class described comprising 35 a block having a flanged base, a tread portion and a web between said base and tread portion, portions of the said web ex- 40 tended from opposite ends of the tread por- 45 tion and provided with slots open at their tops and ends, the upper faces of the web having inclined faces on opposite sides of said slots and adjacent the ends of said web 50 portion, a rail having a hooked extension upon the web portion thereof and with the web of the rail cut away beneath the said hook forming an inclined face therebeneath, the said hook having an inclined inner face, 45 the web of said block having recesses with outer inclined faces and positioned beneath each end of the tread portion and adapted for the reception of said hook with the inclined face of the hook in seating engage- 55 ment with the said recess face and with the rail tread in alinement with the tread of the block.

In testimony whereof I affix my signature in presence of two witnesses.

LOUIS HUNYADI.
